NEW YORK.

BUFFING MECHANISM.

1,303,378.

Specification of Letters Patent. Patented May 13, 1919.

Application filed April 27, 1918. Serial No. 231,107.

To all whom it may concern:

Be it known that I, JOHN F. O'CONNOR, a citizen of the United States, residing at Chicago, in the county of Cook and State of Illinois, have invented a certain new and useful Improvement in Buffing Mechanism, of which the following is a full, clear, concise, and exact description, reference being had to the accompanying drawings, forming a part of this specification.

This invention relates to improvements in buffing mechanism.

The object of the invention is to provide a high capacity friction shock absorbing mechanism having an easy graduated action and which is particularly adapted for buffers of passenger car equipment.

In the drawing forming part of this specification, Figure 1 is a top plan view of a portion of a passenger car end platform casting showing my improved buffing mechanism associated therewith. Fig. 2 is a vertical, transverse, sectional view, taken on the line 2--2 of Fig. 1. And Fig. 3 is a similar view, taken on the line 3--3 of Fig. 1.

In said drawing, 10 denotes the end platform casting of a passenger car and which may be of usual or desired construction, the same being so formed as to provide a longitudinally extending opening 11 for the usual center buffing stem 13. The pocket for the shock absorbing mechanism is formed in the casting in the usual manner and has a front stop wall 16 and rear stop wall 17 with a suitable supporting cross flange 18 on which is riveted a supporting plate 19. The shock absorbing mechanism proper, hereinafter described, is dropped in from the top in the usual manner and the cover or floor plate 20 then put in place. The buffer plate is shown at 21.

The improved shock absorbing mechanism, as shown, includes a casting A having a friction shell and two spring casings formed therein as hereinafter described, a series of friction shoes B, a wedge or pressure-transmitting member C, main springs D--D, preliminary springs F, a front follower G and an abutment member H.

The casting A is of substantially rectangular cross section throughout the greater portion of its length and is formed at its forward end with a spring casing desig-

nated 22 and has seated therewithin the abutment member H. At the rear end of 55 the spring casing 22 the casting A has an integral transverse partition 23 and to the rear of the latter is a second spring casing 24 within which are mounted the twin-arranged main springs D--D, as clearly shown 60 in Fig. 3. As appears from said figure, the springs D--D are inserted laterally into the casing in a manner that will be understood. To the rear of the spring casing 24, the casting A has formed integrally therewith a 65 cylindrical friction shell 25 within which are mounted the circularly arranged series of three friction shoes B and the coöperating wedge or pressure-transmitting member C. The arrangement of friction shoes, 70 wedge, shell 25 and main springs D--D is well known and need not be specifically described.

The member H is provided on its front or outer side with twin-arranged circular 75 flanges 29 to form seats for the rear or inner ends of the two preliminary springs F--F, the forward ends of said springs bearing against the follower G and the latter being spaced from the forward end of the casting 80 A any suitable distance which in actual practice will approximate 3½ inches. There will also be left approximately a distance of 2½ inches between the forward edges of the flanges 29 and the forward edge of the casting A for the purpose hereinafter described. 85

In order to obtain the graduated easy action desirable in buffers for passenger cars and also to maintain the compactness of the device, the member H is shown as provided 90 at the front end thereof with laterally extending shoulders or arms 30--30, the same working in suitable openings in the sides of the front casing 22. These lateral extensions 30 engage shoulders or stops 31--31 formed 95 in the casting 10 so that the member H is prevented from rearward movement.

In absorbing the buffing shocks, inward movement of the main buffer stem 13 forces the follower G rearwardly which will compress the preliminary springs F--F until the follower G engages the front end of the casting A. During this preliminary movement, it is evident that the abutment member H cannot move rearwardly and there is 105 substantially no tendency to move the cast-

2

ing A rearwardly. Consequently there will be no action of the friction mechanism. When the follower G has moved rearwardly sufficiently to engage the casting A, the latter will be forced rearwardly in unison with the follower G and buffer stem 13. This will bring the friction mechanism into active operation inasmuch as the wedge C is held against movement by the rear stop wall 17.

10 Simultaneously with the actuation of the friction mechanism as above described, the preliminary springs F will continue to be compressed due to the fact that the abutment member H remains stationary. From

15 the foregoing, it is evident that for the first part of the buffering action a straight spring capacity is obtained after which a combined friction and spring capacity is obtained which act in tandem and the limit of the

20 compressive action will occur when the follower G has come into contact with the abutment member H, which will preferably be simultaneous with the engagement of the rear end of the casting A with the rear stop wall 17.

25 With the construction above described, it is evident that I obtain a graduated easy action with an ultimate high capacity and furthermore, all minor movements of the

30 buffer plate are absorbed by the preliminary springs F without bringing into play the friction mechanism which is a feature of especial importance in passenger car equipment since it renders the movements of the

35 buffer plates easy in rounding curves and eliminates to a considerable extent the jarring or rattling which frequently occurs in the vestibules of passenger cars. The easy compression of the preliminary springs

40 F—F for a short distance also facilitates the starting of a train of passenger cars where the engineer is compelled to take up the "slack" before driving the engine forwardly.

45 I claim:

1. In a shock absorbing mechanism of the character described, the combination with a member having a friction shell, a spring casing adjacent thereto, and a second spring casing; of friction elements coöperable with said shell and including a pressure-transmitting member; spring means co-acting with said friction elements and disposed within the first named spring casing; an abutment member within the second named spring casing; a preliminary spring within the second named spring casing; and means for maintaining said abutment member and pressure-transmitting member in relatively

50 fixed relation during actuation of said mechanism.

60 2. In a shock absorbing mechanism of the character described, the combination with a member having a friction shell, a spring casing adjacent thereto, and a second spring

casing; of friction elements coöperable with said shell and including a pressure-transmitting member; spring means coacting with said friction elements and disposed within the first named spring casing; an 70 abutment member within the second named spring casing; a preliminary spring within the second named spring casing; and means for maintaining said abutment member and pressure-transmitting member in relatively 75 fixed relation during actuation of said mechanism, said means including lateral extensions from said abutment member coöperable with fixed stops.

3. In a buffering mechanism, the combination with a passenger car end platform casting having a rear stop wall; a buffer stem mounted within said casting; a front follower adapted to be actuated by said buffer stem; a friction mechanism including main 80 resisting springs, a friction shell, friction shoes coöperable with the shell, and a pressure-transmitting element, said element being normally in engagement with said stop wall, of a preliminary spring engaging said 85 follower at its front end, an abutment member engaging the rear end of said preliminary spring and disposed forwardly of the friction mechanism, and means for holding said abutment member stationary during 90 the actuation of the buffer, said friction mechanism being actuated after the preliminary spring has been partly compressed.

4. In a buffering mechanism, the combination with a passenger car end platform casting having a rear stop wall; a buffer stem mounted within said casting; a front follower adapted to be actuated by said buffer stem; a friction mechanism including main 100 resisting springs, a friction shell, friction shoes coöperable with the shell, and a pressure-transmitting element, said element being normally in engagement with said stop wall, of a preliminary spring engaging said 105 follower at its front end, an abutment member engaging the rear end of said preliminary spring and disposed forwardly of the friction mechanism, and means for holding said abutment member stationary during 110 the actuation of the buffer, said friction mechanism being actuated after the preliminary spring has been partly compressed, said means including extensions on said second follower and coöperable shoulders on 115 said platform casting.

5. In a shock absorbing mechanism of the character described, the combination with a casting having a friction shell at one end, a spring casing open at the other end, and a second spring casing in communication 120 with the friction shell and separated from the first named spring casing by a transverse partition; of friction elements coöperable with said friction shell and including a pressure-transmitting member extended 125 130

beyond the adjacent end of the shell; of main springs coöperable with said friction elements and disposed within the spring casing adjacent the shell; an abutment member mounted within the end spring casing of said casting; preliminary spring means mounted within the end spring casing and

engaging said abutment member, said preliminary spring means extending beyond the adjacent end of the casting. 10

In witness that I claim the foregoing I have hereunto subscribed my name this 10th day of April, 1918.

JOHN F. O'CONNOR.
